UNITED STATES PATENT OFFICE.

HENRY C. SCHRADER, OF WHEELING, WEST VIRGINIA.

DESIGN FOR THE SURFACE ORNAMENTATION OF TABLE-WARE.

SPECIFICATION forming part of Design No. 19,842, dated May 13, 1890.

Application filed November 7, 1889. Serial No. 329,573. Term of patent 3½ years.

To all whom it may concern:

Be it known that I, HENRY C. SCHRADER, a citizen of the United States, residing at Wheeling, in the county of Ohio, State of West Virginia, have invented and produced a new and original Design in the Surface Ornamentation of Table-Ware, of which the following is a specification, reference being had therein to the accompanying drawings.

10 Figure 1 is a vertical section through the goblet or bowl showing my design. Fig. 2 is an enlarged view of a portion thereof.

15 The leading feature of the design consists in a plurality of raised elongated tapered globules.

20 A is the table article, which in this instance I have chosen to show as a goblet or sugar-bowl, merely for the purpose of illustrating my design.

25 The outlines of the design are more clearly represented in Fig. 2, to which particular reference is called. In this figure, as well as in Fig. 1, I have shown four globules B in a set, with the butts or enlarged portions arranged innermost or at the center and their points 25 outward. The boundary of each set of globules defines a circle which is inclosed within a rectangular outline.

What I claim as new is--

30 The design for the surface ornamentation of table-ware, substantially as herein shown and described.

In testimony whereof I affix my signature in presence of two witnesses.

HENRY C. SCHRADER.
